ATTORNEY

Leigh Hayes

WITNESS:

UNITED STATES PATENT OFFICE.

ALBERT J. FEASTER, OF SALISBURY, NORTH CAROLINA.

BRACE.

Application filed October 9, 1926. Serial No. 140,616.

This invention relates to braces primarily adapted to support the body and rest the back of a person in a stooping posture in the instance of harvesting, thereby overcoming the usual necessity of resting an elbow upon the knee.

An object of the invention comprehends means for checking the angular position of the brace to withstand the weight of a person.

A further object of the invention contemplates means for retracting the brace from an angular position to its normally inoperative position.

More specifically stated the invention embodies means engageable with the chest, under the arm-pits and at points upon the legs above the knees to support the body in a forwardly stooping posture.

With the above and other objects in view, the invention further consists of the following novel features and details of construction to be hereinafter more fully described, illustrated in the accompanying drawings, and pointed out in the appended claims.

In the drawings:

Figure 1 is illustrative of the application of the invention.

Figure 2 is an elevation of the invention.

Figure 3 is a sectional view taken through the device per se.

Figure 4 is an enlarged sectional view illustrating the checking means.

Figure 5 is an elevation of a connecting member for the extremities of the brace.

Referring to the drawings in detail, wherein like characters of reference denote corresponding parts the reference character 10 indicates a substantially inverted Y-shaped body member terminating to provide a bifurcated end portion 11 upon the extremity thereof. Leg members 12 form hinge barrel connections 13 within the lower ends of the body. Pockets 14 are formed within the upper ends of the legs adjacent the connection therefor. The body portion 10 being hollow and having a plate member 15 disposed axially of the longitudinal center thereof and falling short of the entire length of said body portion adjacent the bifurcated extremity thereof. Roller members 16 are journaled within the lower ends and upper extremities of the body portion, the purpose of which will be presently apparent.

A connecting element 17 provides a bifurcated portion upon one end forming oblique-

ly disposed legs 18 received and fixed within the pockets 14 of the aforementioned legs 12. The upper portions of said legs 18 are passed over the lowermost of the roller members 16 while the solid portion of the element is passed upwardly within the hollow portion of the body 10 in advance of the plate member 15 and rearwardly over the uppermost of the roller members 16. A retractile spring 19 carried within the body 10 is connected with the remaining extremity of said connecting element to render the same taut and to normally tension said legs 12 in direct alignment with that of the body portion 10. The lower extremities of said legs 12 also terminate in bifurcated end portions 20. An arcuate-shaped plate 21 providing an apertured ear 22 at an appropriate point in its length and upon the forward side thereof is pivotally mounted within the bifurcated portion 11 upon the upper extremity of the body portion 10. An adjustable strap member is attached to the ends of said arcuate-shaped plate to secure the latter across the chest of a person and under the arm-pits. Semicircular plates 23 are likewise pivotally mounted within the bifurcated portions 20 of the legs 12 and which include strap members for attaching said plates upon the legs immediately above the knees to permit the body to freely bend to a posture similar to that as illustrated in Figure 1 of the drawings.

In order to relieve the tension of the spring from the body of the wearer when the invention is called into use I provide a check in the form of a lever 24 pivoted within the body portion 10 and having an inwardly offset portion 25 adapted for selective reception within any one of the plurality of apertures provided at an appropriate point in the length of the connecting element 17. A leaf spring 26 carried within the body portion and engageable with said lever 24 acts as a detent therefor to normally tension said offset end portion inwardly toward the connecting element and within one of the apertures thereof. A disk 27 is carried upon one end of the lever 24 exteriorly of the body to facilitate the operation of said lever from the outside.

In carrying out the invention it is to be noted that the invention is particularly applicable for use by laborers while harvesting whereas it is incumbent to keep the body in a half-stooping position for long periods

of time. The back becomes tired, and an elbow is set akimbo upon the knee to rest the back. The back will then have the strain of the posture upon one side. 5 With the invention applied the wearer may grasp the body portion and depress the disk member 27 thereby releasing the inwardly offset portion 25 of the lever 24 from the particular aperture of the 10 connecting element 17 thereby permitting the compression spring 19 to become uncoiled and exercising a tight pull upon the connecting element 17 moving in an opposite direction with respect thereto. When the 15 wearer has stooped in a desired posture the disk member 27 is released and the inwardly extending offset portion 25 of the lever 24 is received within one of the apertures in the connecting element 17 whereby the tension of the retractile spring 19 will be released from the body portion, and legs 12 carried thereby. The weight of the wearer's 20 body is upon the arcuate-shaped plate 21 and is directed upon the legs of the wearer by 25 the semicircular plates 23 attached thereto. The body and back as well as the joints at the knees and hips will be relieved from undue strain and the laborer will be permitted to work more steadily inasmuch as laborers 30 usually have to frequently erect themselves to a standing position and sway backwardly to relieve the back.

The invention is susceptible of various 35 changes in its form, proportions and minor details of construction and the right is herein reserved to make such changes as properly fall within the scope of the appended claims.

Having thus described my invention, what is claimed is:

1. In a device of the character described comprising a brace having a hollow body portion, leg members carried thereby and adapted for swinging movement thereon, a connecting element for the body and legs, a 45 spring member connecting said element with the body, and attaching means carried upon the extremities of the body and legs.

2. A brace comprising a hollow body portion of substantially inverted Y-shaped formation, legs hingedly mounted upon the lower extremities of the body portion, a connecting element attached to the legs and passed within the body portion, a retractile 55 spring carried by the body portion and connected with said element to normally position said legs in alignment with the body, and attaching means carried upon the extremities of the body and legs respectively.

3. A body brace of the character described comprising a hollow member of substantially Y-shaped configuration, leg members mounted upon the lower extremities of the member, a connecting element forming bifurcated portions connected with the legs and carried within the member, a retractile spring connecting the opposed end of the element to regulate the normal position of said legs, attaching means carried upon the free ends of the member and legs, and means carried by the member and adapted for cooperation with said connecting element to relieve the tension of the spring from the body of the wearer.

In testimony whereof I affix my signature.
ALBERT J. FEASTER.
